UNITED STATES PATENT OFFICE.

WILLIAM MILLER, OF GILMAN, MONTANA.

AUTOMATIC AIR-BRAKE SYSTEM.

1,104,693.

Specification of Letters Patent. Patented July 21, 1914.

Application filed November 7, 1913. Serial No. 799,773.

To all whom it may concern:

Be it known that I, WILLIAM MILLER, a citizen of the United States, residing at Gilman, in the county of Lewis and Clark and State of Montana, have invented certain new and useful Improvements in Automatic Air-Brake Systems; and I do hereby declare the following to be a full, clear, and exact description of the invention, such as will enable others skilled in the art to which it appertains to make and use the same.

This invention comprehends improvements in airbrake systems for use in connection with vehicles, such as trolley and railway cars, and relates more particularly to such a system as will automatically operate to stop a train when a predetermined speed has been reached.

One of the objects of the invention is to provide in a system of this nature a brake cylinder into which air is continually forced by a traction operated pump, the pressure within the brake cylinder being dependent upon the speed at which the vehicle is traveling and this cylinder being provided with a discharge valve which will automatically close when the train is traveling at such a speed as to produce a predetermined pressure within the cylinder.

Another object of the invention is to provide in an airbrake system of this nature, means whereby the brakes may be applied at any time by manually closing an air valve.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a vertical longitudinal sectional view through a car, showing in elevation my improved airbrake system applied thereto, Fig. 2 is a vertical longitudinal sectional view, partly in elevation showing the construction of the pump and brake cylinder, and Fig. 3 is a fragmentary detail sectional view, showing the automatically operated valve which closes the discharge from the brake cylinder, whereby the brakes are applied.

Referring in detail to the drawings by numerals, 5 designates, as an entirety, a car

body and 6 designates the supporting wheels for the car.

In carrying out my invention, I provide a brake cylinder 7, having two discharge ports 8 and 9 formed in one end thereof and being also provided with an intake port 10 through which air is forced from a pump 11. As shown in Fig. 2, the pump is of the double acting type, having a pair of intake ports 12 and a pair of discharge ports 13, the air flowing through the latter being conducted into the brake cylinder through the ducts 14 and 15. It will be understood that the pump and brake cylinder may be of any preferred construction, that they may be placed in any desired position with respect to each other and that the manner in which they are supported upon the car is immaterial. In the present instance I have shown the pump positioned above the brake cylinder and straps 16 surrounding the brake cylinder, whereby the latter is secured to the bottom of the car 5.

The piston 17 of the pump is operated by means of a connecting rod or pitman 18 connected at one end to the crosshead 19 and at its other end to a friction wheel 20 carried upon the inner end of a lever 21. The friction wheel 20 is adapted to engage a similar wheel or disk 22 which is secured to the rotatable axle 23. In order that the wheel 20 may be thrown into engagement with the wheel or disk 22, or held from engagement therewith, I provide a vertical rod 24 having a hand wheel 25 secured to its upper end and being connected at its lower end to the forward or outer end of the lever 21. This rod is threaded intermediate its ends, as indicated by the numeral 26 and the threaded portion works through a sleeve or nut 27 rigidly secured in the floor of the car, so it will be apparent that a rotation of the rod 24 will either raise or lower the wheel 20. When the two friction wheels are engaged and the car is in motion, the piston 17 will be continually operated to force a steady stream of air into the forward end of the brake cylinder 7. Now when sufficient pressure is obtained within the cylinder 7, the piston 28 will be forced rearwardly against the tension of the spring 29, causing the brake block or shoe 30 to engage the wheel and slow down the car. Any system of levers, which are suitable for the purpose, may be employed for connecting the piston rod 31 and the brake shoe 30.

100
105
110

For the purpose of illustration I have shown a pair of levers 32 pivoted intermediate their ends and connected by a rod 33.

To automatically close the exhaust ports 9 of the brake cylinder 7 when a certain definite pressure has been created within the cylinder, I employ a valve 34 having a stem 35. The valve is held in alignment with the port 9 and is adapted to seat against the beveled portions 36 of the walls thereof, as will be clearly apparent upon reference to Figs. 2 and 3. To hold the valve in its proper position, I employ a U-shaped frame 37, the ends of which are connected to the cylinder head on opposite sides of the port 9. A guide 38 connects the arms of the frame 37 and is centrally apertured to permit the passage of the valve rod 35, said rod also extending through an opening 39 in the central portion of the frame. The valve stem 35 is threaded and carries nuts 40 and 41, the latter of which bears against an expansive spiral spring 42 coiled about the stem between the guide 38 and the central portion of the frame. The nut 41 is used to adjust the tension of the spring 42 so that the valve 34 may be caused to close when any predetermined pressure is created within the cylinder 7.

30 A pipe 43 leads from the discharge port 9 along the bottom of the car and then upwardly through the same, as indicated by the numeral 44, and has a valve 45 connected to its free extremity. A second pipe 46 is connected to the discharge port 8, extends parallel to the pipe 43 and carries a valve 47 on its extremity.

Having described the construction of my improved airbrake system, it now remains 40 to explain the operation thereof: When the system is in its normal working order, the valves 34 and 45 are open and the valve 47 closed. Now supposing, for example, the spring 42 to be adjusted so the valve 34 will 45 close when a pressure of fifty pounds per square inch has been produced in the cylinder 7, said pressure being caused by the pump when the car is running at a speed of seventy-five miles per hour. Then for any 50 speed below this rate, the pressure will be below fifty pounds per square inch and the valve 34 will remain open, allowing the air in the brake cylinder to escape through the pipe 43 and valve 45. When the car or 55 train reaches a speed of seventy-five miles per hour, the valve 34 will close, whereupon the pressure within the cylinder 7 will rapidly increase, causing the piston 28 to move rearwardly and force the brake shoe 30 against one of the wheels and so reduce the speed of the vehicle. This same result can 60 be produced by closing the valve 45 and therefore it will be obvious that the brakes may be applied irrespective of the speed 65 of the car. To release the brake, the valve

47 is opened to allow air to escape from the brake cylinder 7 and then when the valve 45 has again been opened, the system is in its normal position and will again automatically operate to stop the car when a predetermined speed has been reached.

From the foregoing description taken in connection with the accompanying drawings, it will be apparent that I have provided a very simple, efficient and reliable 75 air brake system and it will be understood that various changes in the construction, position and size of the various parts may be changed without departing from the scope and spirit of the invention as claimed.

Having thus described my invention, I claim:—

1. In an airbrake system, the combination of a brake cylinder, a traction operated pump adapted to force air into said cylinder, the cylinder being formed with a discharge port, a valve automatically operated by the pressure within the brake cylinder to close said discharge port, a piston positioned within the brake cylinder, a brake shoe means operatively connecting the piston and brake shoe, whereby a movement of the piston in one direction will cause the brake shoe to become operative and valve mechanism operable independently of said valve to 95 reduce the pressure within the cylinder.

2. In an airbrake system of the character described, the combination with a car, of a brake cylinder, a traction operated pump adapted to force air into said cylinder, the cylinder being formed with a discharge port, an adjustable valve positioned within the cylinder to automatically close the discharge port when a fixed pressure is obtained within said cylinder, a piston operable 100 within the brake cylinder, and brake mechanism operatively connected to said piston.

3. In an airbrake system of the character described, the combination with a vehicle, of a brake cylinder, a traction operated pump connected to said cylinder, the cylinder being formed with a pair of discharge ports, a manually operated valve normally closing one of said ports, a second valve adapted to automatically close the other 110 discharge port when the pressure within the brake cylinder reaches a certain degree, a piston operable within the brake cylinder, and brake mechanism connected to said piston, the piston operating when the second 115 mentioned valve is closed to apply the brakes.

4. In an airbrake system of the character described, a brake cylinder, means for forcing air into said cylinder, brake mechanism actuated by certain predetermined pressure within the brake cylinder, said cylinder being formed with a pair of discharge ports, a manually operated valve for closing one of said ports, a spring pressed valve adapted to 125 130

close the other of said ports when a fixed pressure is created in the brake cylinder, and spring means connected to said second mentioned valve, whereby the pressure necessary to close said valve may be regulated.

5. In an airbrake system of the character described, a brake cylinder, a means for forcing air into said cylinder, the cylinder being formed with a pair of discharge ports, 10 manually operated means for opening and closing one of said ports, a valve positioned within the cylinder to close the other of said ports when a certain pressure is created within said cylinder, a valve stem se-

cured to said valve, a U-shaped frame 15 through which the valve stem extends, spring means for holding the valve normally open, adjusting means whereby the tension of said spring means may be varied, brake mechanism operable when said second mentioned valve is closed, and means for manually closing the second mentioned ports. 20

In testimony whereof I affix my signature in presence of two witnesses.

WILLIAM MILLER.
